UNITED STATES PATENT OFFICE

2,580,471

MEANS FOR HANDLING PIPES OR CONDUITS

Luke E. Smith, Denver, Colo., assignor to Quick-Way Truck Shovel Co., Denver, Colo., a corporation of Colorado

Application August 27, 1947, Serial No. 770,893

6 Claims. (Cl. 214—131)

1

The present invention relates to means for handling pipe or conduit. It has to do particularly, although not exclusively, with means associated with a power shovel in the form of an attachment to the boom and dipper stick of a trench hoe, or the like, for handling long sections of heavy pipe, conduit, rods, or poles, whereby the pipe, or the like, can be loaded onto a truck or unloaded therefrom, or lowered into place in a trench, or removed from said trench, this being accomplished without the necessity of any manual handling of said pipe.

One of the objects of the present invention is to provide improved means adapted to be associated with the boom and trench hoe or shovel dipper stick of a power shovel, for converting said power shovel into an improved hoist and handling means for sections or lengths of pipe, conduit, or the like.

Another object of the invention is to provide relatively simple and inexpensive means for effecting the conversion referred to in the preceding paragraph.

A further object of the invention is to provide improved means for converting a power shovel into a pipe or conduit handling means, in which said improved means may be quickly and easily attached to hold the power shovel boom and the trench hoe dipper stick in rigid cooperative relationship, and to permit ready release of the same so that the boom and dipper stick may be again employed in conventional manner when desired.

The foregoing and other objects and advantages of the present invention will appear from the following description and appended claims when considered in connection with the accompanying drawing wherein like reference characters designate corresponding parts in the several views.

In said drawing:

Fig. 1 is a side elevational view of a portion of a power shovel including the boom and a trench hoe unit, showing one application of the present invention thereto; and

Fig. 2 is a fragmentary enlarged side elevational detail view of a portion of the means for converting a conventional power shovel structure into means for handling pipe, conduit, or the like.

Before explaining in detail the present invention it is to be understood that the invention is not limited in its application to the details of construction and arrangement of parts illustrated in the accompanying drawing, since the inven-

2

tion is capable of other embodiments and of being practiced or carried out in various ways. It is to be understood also that the phraseology or terminology employed herein is for the purpose of description and not of limitation, and it is not intended to limit the invention claimed herein beyond the requirements of the prior art.

Referring now particularly to the drawing, there is shown at 10 the rear portion of the cab of a power shovel as manufactured and sold by Quick-Way Truck Shovel Company of Denver, Colorado. Within the cab 10 there is located the conventional mechanism for operating the boom and trench hoe and including a winding drum or drums for handling the cable or cables forming a part of the power shovel mechanism.

Pivotaly mounted in conventional manner to the rear end of the power shovel is a boom 11 having at its outer end a boom point 12. The boom 11 carries, as shown, a trench hoe unit, shown as a whole at 13, which comprises a bucket or trench hoe 14, a dipper stick 15, and a pair of reinforcing bars or braces, one such being shown at 16. The dipper stick 15 is provided with a point 17 projecting beyond the end thereof and with a hinge or bracket member 18 at one side of the stick and adjacent the point 17. This hinge member or bracket 18 is pivotally connected to the boom point 12 by a pin or bolt 19, thus permitting the trench hoe unit or assembly 13 to be swung in an upright arc relative to the boom 11. The dipper stick point 17 carries a pulley or sheave 20 connected by a cable 21 to a sheave 22 located, as shown, on the rear wall of cab 10.

The boom 11 carries a guide pulley 23 over which a cable 24 travels to and over a fixed pulley or sheave assembly (not shown) and which is preferably attached to the braces 16, and thence back to pulley 23. A pulley block 25 is attached by means of a hook 26 to one of the trench hoe unit brace members 16, preferably adjacent the fixed pulley (not shown). The cable 24 extends from a winding drum (not shown) located within the cab 10. The sheave assembly or pulley block 25 is added to the conventional structure and forms a part of the pipe or conduit handling means of the present invention, described below. Because of the presence of the members 25 and 26 and of the brace 16, the fixed pulley cannot be seen; nor can the portions of cable 24 which enter and engage said fixed pulley.

In the conventional power shovel structure, the cable 24 would extend over the guide pulley 23 and over a sheave or pulley (not shown) arranged

within a so-called equalizer (not shown) located at the upper portion of the trench hoe 14.

In addition to the cable 24, a cable 27 which runs over pulleys or sheaves 28 and 29 carried by the cab 10, runs to and over the block pulley 25 and carries at its end a connecting member or coupling 30 having a depending hook 31. By manipulating the cable 27, it will be seen that the coupling member 30 and the hook 31 may be raised or lowered.

As shown, the hook 31 has a grappling device or sling removably attached thereto which preferably comprises a looped portion 33 of a cable or heavy wire 34 whose outer ends carry steel hook members or clamps 35. These hooks or clamps are adapted to grip the opposite end edges of a length or section of metal pipe or conduit 36, see Fig. 1. In normal operation, as a trench hoe or similar material handling scoop or scraper, the dipper stick 15 would be free to pivot about the pin or pivot point 19. In accordance with the present invention, however, this dipper stick 15 is prevented from having such pivotal or swinging movement relative to boom 11. For this purpose, a two-part steel clamp 40 is secured by bolts or the like 41 to the boom 11 adjacent its point 12. One section of the clamp 40 carries an outward projection or bracket-like portion 40a to which is swingably attached a threaded rod, bolt, or connecting bar 42. The rod 42 is adapted to be engaged with a slot (not shown) formed in the dipper stick point 17 and to be held in rigid relationship with said point by a nut 43. Thus, when the attaching member 42, 43 is in its operative position as seen in the drawing, the trench hoe assembly 13 will be held in a non-movable elevated position. In this position of the parts or units, the structure provides convenient means for supporting the mechanism which serves to convert the conventional power shovel into the pipe or conduit handling means embodying the present invention.

In operation, the sling or pipe gripping device 33, 34, 35 is applied or attached to a pipe section, such as that shown at 36. The hook 31 of the hoist is then engaged with the cable loop 33, and the hoisting drum (not shown) within the cab 10 is operated to raise or lower the pipe section as desired.

When and if it is no longer desired to employ the apparatus shown in the drawing for handling pipe or conduit, the block pulley 25, the coupling 30 and hook 31 and their associated cable 27 may be detached by releasing the hook 26. The sling 33, 34 and 35 may be released from hook 31. The supporting link or connecting member 42 would now be released from engagement with the dipper stick point 17 and, if desired, the clamp 40 entirely removed from the boom. This would permit the unit 13 to be used in its usual or conventional manner.

The shovel unit 13 is prevented from being swung upwardly beyond the position in which it is shown in Fig. 1 of the drawing by virtue of a stop member 44 carried by the boom and which is engaged by the dipper stick point 17.

From the foregoing it will be seen that by virtue of the present invention, it is a relatively simple matter to convert a conventional power shovel into a pipe or conduit handling hoist means and to reconver the same to its conventional shovel structure.

Having thus described the invention, what is claimed is:

1. Detachable means for connecting together the boom and pivoted dipper stick assembly of a power shovel to maintain the stick assembly in its raised position to thereby convert said boom and stick assembly into means for supporting article handling equipment, comprising a clamp carried by the boom adjacent its point, and a connecting bolt and nut assembly pivotally attached to said clamp and engageable with an adjacent portion of the stick assembly.

2. Detachable connecting means according to claim 1, wherein a stop member is disposed between the boom and pivoted dipper stick assembly to limit the upward movement of the latter relative to the former.

3. Detachable means for connecting together the boom and pivoted dipper stick assembly of a power shovel to maintain the stick assembly in raised position to thereby convert said boom and stick assembly into means for supporting article handling equipment, comprising a two-part clamp removably carried by the boom adjacent its point, and a connecting bolt and nut assembly pivotally attached to said two-part clamp and engageable with the dipper stick assembly.

4. Detachable means for connecting together the boom and pivoted dipper stick assembly of a power shovel according to claim 3, wherein a stop member is disposed between the boom and the dipper stick point to limit the upward movement of the dipper stick assembly relative to the boom.

5. Means for converting a power shovel into an article handling apparatus in which the power shovel includes a boom and a trench hoe unit swingably mounted upon the outer end of the boom; said converting means comprising a clamp engageable with the boom, and a connecting rod carried by the clamp and detachably engaging a portion of the trench hoe unit to maintain said unit in a raised position, said trench hoe unit providing means for removably supporting article handling equipment in suspended condition.

6. Means for converting a power shovel into an article handling apparatus in which the power shovel includes a boom and a trench hoe unit swingably mounted upon the outer end of the boom; said converting means comprising a clamp engageable with the boom, and means movably carried by the clamp and detachably engaging a portion of the trench hoe unit to maintain said unit in a raised position, said trench hoe unit providing means for removably supporting article handling equipment in suspended condition.
